UNITED STATES PATENT OFFICE.

ROBERT M. PIERSON, OF AKRON, OHIO, ASSIGNOR TO THE B. F. GOODRICH COMPANY,
OF NEW YORK, N. Y., A CORPORATION OF NEW YORK.

DESIGN FOR A TIRE CASING.

Application filed October 18, 1921. Serial No. 508,616. Term of patent 14 years.

To all whom it may concern:

Be it known that I, ROBERT M. PIERSON, a citizen of the United States, residing at Akron, in the county of Summit and State of Ohio, have invented a new, original, and ornamental Design for Tire Casings, of which the following is a specification, reference being had to the accompanying drawings, forming a part thereof.

Fig. 1 is a plan view of a portion of a tire casing showing my design.

Fig. 2 is a cross-section on the line 2—2 of Fig. 1, omitting internal structural details.

I claim:

The ornamental design for a tire casing as shown.

ROBERT M. PIERSON.
